(57) CLAIM

The ornamental design for an animal carrying bag, as shown and described.

DESCRIPTION

FIG. 1 is a front elevational view of an animal carrying bag showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view thereof;

FIG. 8 is another perspective view thereof; and,

FIG. 9 is a perspective view of the animal carrying bag where the animal carrying bag is in a configuration of use. The dog shown in light gray in FIG. 9 depicts environment and forms no part of the claim.
